CLAIM

The ornamental design for a communications gateway, as shown and described.

DESCRIPTION

FIG. 1 is a perspective view of a communications gateway according to the invention;

FIG. 2 is a right side elevational view of the communications gateway;

FIG. 3 is a left side elevational view of the communications gateway;

FIG. 4 is a front elevational view of the communications gateway;

FIG. 5 is a rear elevational view of the communications gateway;

FIG. 6 is a top view of the first the communications gateway; and,

FIG. 7 is a bottom view of the communications gateway.
